UNITED STATES PATENT OFFICE.

GEORGE W. HUEY, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTRODE FOR SLIP-REGULATORS.

1,248,495.

Specification of Letters Patent.

Patented Dec. 4, 1917.

Application filed June 18, 1913. Serial No. 774,371.

To all whom it may concern:

Be it known that I, GEORGE W. HUEY, a citizen of the United States, and a resident of Wilkinsburg, in the county of Allegheny and State of Pennsylvania, have invented a new and useful Improvement in Electrodes for Slip-Regulators, of which the following is a specification.

My invention relates to electrodes for slip regulators and it has for its object to provide a device of the above indicated character which is simple in structure and which will improve the operating conditions of such regulators.

In the use of slip regulators, as at present constructed, unsatisfactory operating conditions are often encountered because of polarization or the collection of bubbles of gas upon the electrodes. The area of contact surface of the electrodes is thereby decreased, and the resistance of the device is correspondingly increased, rendering the device uncertain in its action and preventing uniformity of its effect upon the electrical circuit in which it may be connected. This is especially true in connection with such electrodes as are so shaped or arranged as to cause bubbles to collect gradually until they coalesce and escape to the surface of the liquid suddenly.

I propose to avoid the above mentioned defects by providing an electrode having a structure upon which the bubbles, the formation of which is incident to the operation of such devices, have practically no tendency to adhere, while the dispersal of the bubbles is uniform and at a rate corresponding to their formation.

My invention will be described in detail in connection with the accompanying drawings in which Figure 1 is a side view, partially in elevation and partially in section, of a unit of a slip regulator embodying my invention. Fig. 2 is a top plan view of a regulator electrode.

The regulator unit 1 comprises a vessel 2 which contains a suitable liquid or electrolytic solution. The stationary electrode comprises a plate 3 which is located near the bottom of the vessel 2, where it is completely immersed in the liquid, and which is provided with a terminal 4 that extends

through the base 5 of the vessel 2. The movable electrode comprises a series of concentric rings 6 which are attached to cross bars 7, and a rod 8 upon which the bars 7 are threaded at their respective centers. The rod 8 may be actuated by any suitable means (not shown) to raise and lower the electrode to vary the resistance of the regulator, as desired.

When the regulator is connected in circuit and bubbles form on the vertical surfaces of the several rings 6, they are free to pass at once to the surface of the liquid, the top of the electrode being practically open. There is no obstruction to this movement of the bubbles as is the case with electrodes having the form of horizontal plates or grids, the horizontal surfaces of which are in contact with the water and thus serve to trap the minute bubbles until they accumulate in such large number as to coalesce and escape. The result is to secure a uniformity of action that is not possible with the ordinary construction.

An electrode constructed in accordance with my invention has a very compact form, presenting a relatively large area of contact surface as compared with its horizontal dimensions. Owing to the large contact surface per unit of depth, the adjustment required for changes of resistance is relatively small.

Many changes will occur to those skilled in the art to which my invention appertains, and it is understood that such changes may be made as fall within the limits of the appended claims.

I claim as my invention:

1. An electrode comprising a plurality of hollow cylindrical contact members concentrically arranged in a horizontal plane, a rod having its axis coincident with that of the contact members, and means for connecting said contact members to said rod.

2. An electrode comprising a plurality of hollow conducting members of different sizes, each member surrounding that of the next smaller size, conducting means rigidly connecting relatively small portions of the top edges of said members, and a connecting rod having one end joined to said means.

3. An electrode comprising a plurality of

hollow conducting cylinders of different diameters, each cylinder surrounding that of the next smaller size, a relatively narrow conducting bar connecting the top edges of said cylinders, and a conducting rod extending substantially parallel to said cylinders and secured to said bar.

In testimony whereof, I have hereunto subscribed my name this 7th day of June, 1913.

GEO. W. HUEY.
